UNITED STATES PATENT OFFICE

HERMANN DEUTSCH, OF GROSS-LICHTERFELDE, NEAR BERLIN, GERMANY, ASSIGNOR,
BY MESNE ASSIGNMENTS, TO PENCIL MECHANISM CORPORATION, OF NEW YORK,
N. Y., A CORPORATION OF NEW YORK

MECHANICAL PENCIL

Application filed April 24, 1925, Serial No. 25,546, and in Germany May 8, 1924.

My invention relates to mechanical pencils, particularly of the step-by-step type, and in certain of its aspects to mechanical pencils of the magazine type.

An object of the invention is to provide an improved type of step-by-step pencil, wherein in the lead is fed with ease and certainty. Another object is to provide a step-by-step pencil which is simple in construction, and which can be easily and economically manufactured and assembled. A more specific object of the invention is to provide a pencil of the type having two telescoping tubes wherein the feeding of the lead is brought about by moving the inner tube toward the point of the pencil. Other objects of the invention will in part be obvious and will in part appear hereinafter.

In the particular embodiment of my invention exemplified, there is provided at the lower end of an inner tube, a hollow cylinder at the end of which is formed a conical seat and this seat is adapted to receive the ends of a gripper which form a pair of resilient jaws adapted to engage the leads. When the device is in operative position, the said jaws which are conical at the outside, fit in said seat and are tightly held against the lead. Preferably, the pressure with which the jaws engage the lead is increased by so bending the arms which support said jaws that their upper ends are engaged by the bore of the hollow cylinder so that the cylinder assists the said seat in closing the jaws.

Relative longitudinal movement of the hollow cylinder and the gripper is effected when the pencil is operated and the lead is no longer fed after the gripper has performed its downward motion. The hollow cylinder is positively connected with the inner tube and carries along the gripper by friction for a distance limited by a check on the outer tube. The gripper is arrested by said check before the inner tube and the hollow cylinder have completed their downward stroke, and its jaws are released by the conical seat of the hollow cylinder. At the same time, the arms of the gripper are also released by the bore of the cylinder and the lead is no longer fed. When the inner tube is released it is

returned to its initial position by a push-back spring and carries along with it the opened gripper until said gripper engages a check on the outer tube and is arrested. On continued upward motion of the hollow cylinder the latter compresses the arms on which the jaws are formed, and the jaws themselves so that the lead is firmly held in its advanced position. 55

In the drawings, devices embodying my invention are illustrated by way of example.

Fig. 1 is a longitudinal section of the pencil, ready for use,

Figs. 2 and 3 are similar sections of its lower end, on a larger scale, showing the jaws 65 closed and open, respectively,

Fig. 4 is a longitudinal section at right angles to the section in Fig. 2,

Fig. 5 is a cross section on line 5—5 on Fig. 2 and Fig. 4, 70

Fig. 6 is a longitudinal section of the gripper,

Fig. 7 is a section of one of its jaws,

Fig. 8 is a longitudinal section of a modified form of pencil, ready for use, 75

Fig. 9 is a similar section, showing the modified form of pencil inverted and being charged with a fresh lead,

Fig. 10 is an elevation of the upper end of the modified form of pencil after its cap has 80 been unscrewed,

Fig. 11 is a longitudinal section of the upper end of the inner tube, on a larger scale,

Fig. 12 is a plan view of said tube end.

Referring first to Figs. 1 to 7, *a* is the outer and *b* the inner tube, and *c* is a knob or the like secured to the upper end of the inner tube. The lower end of the outer tube is conical and abuts against a shoulder on a point 6 of strong material which is screwed into a conical body *d*. The body *d* supports a tube *e* in which the leads are guided. The tube is slotted at *f* and to its upper end is secured a disc *g* which is slightly dished towards its centre and forms the bottom of a magazine *h* for the supply leads *i*. The leads are guided toward the centre of the disc *g* and into the tube *e*. 95

A tubular check *k* is secured to the tube *e* 100

and a disc *l* slotted at *m* is formed at one end of the check *k*.

A gripper *n* is free to slide on the tube *e*. The gripper comprises a tubular portion *o* and two arms *p* of resilient material at the ends of which jaws *q* having conical outer faces are formed. The jaws *q* are considerably narrower than the arms *p* and pass through the slots *f* in the tube *e* the width 10 of which is just sufficient to allow the jaws to pass. The faces of the jaws are serrated on the inside at *q'* as shown in Figs. 4 and 5 so that they are capable of securely holding the leads *r* (or the dummy 10 in the modified 15 form) in the tube *e*. The arms *p* are wider than the jaws *q* as will be seen in Fig. 4 so as to impart to them a greater resistance to bending than if they were the same width as the jaws *q*.

20 A hollow cylinder *s* is secured to the lower end of the inner tube *b* by struck in portions *u* at the lower end of the inner tube *b*, so they enter a groove *v* near the end of the cylinder *s*. The bore of the cylinder is formed with a conical seat *w* at its lower end.

25 The seat *w* is extended into a tubular extension of the part of the cylinder *s* around which is placed the end of a spring *x* the other end of which abuts against a shoulder 30 *y* on the conical body *d*.

35 The arms *p* of the gripper *n* are bent outwardly at *z*, so that the bent portions of the arms are engaged by the inner wall of the hollow cylinder *s* when the parts are in the position shown in Fig. 2. Thus the threaded faces *q'* of the conical portion *q* of the gripper *n* are held more firmly against the lead.

40 The operation of my improved pencil is as follows:

45 When the end of the lead *r* has become worn off the knob *c* is depressed so that the inner tube *b* is displaced in the outer tube *a*, and the hollow cylinder *s* is carried downwards with the tube *b*. The gripper *n* is also moved downwards by reason of friction 50 between the cylinders and the arms and jaws at *z* and *q* and the lead *r* is fed forward until the tubular portion *o* of the gripper *n* abuts against the upper end of the tubular check *k* on the tube *e*. When the tube *b* is further depressed, it and the hollow cylinder *s* will move downwardly away from the jaws until the cylinder *s* abuts against the end 2 of the tube 3 which is formed about the base of the tube *e*. This downward movement of the cylinder *s* permits the jaws *q*, because of the resiliency of their arms, to open and release 55 the lead.

60 When the hollow cylinder *s* has attained its final or low position and the pressure on the knob *c* ceases, the spring *x* returns the parts to their initial position, the jaws of the gripper *n* remaining open until the end of the tubular portion *o* abuts against the disc *q*. 65 The ends of the jaws are then engaged by the

shoulder 4 of the seat *w* and the shoulder 5 at the end of the hollow cylinder *s* engages the kinks *z* of the arms *p*. When the upward movement of the gripper is arrested by the disc *g*, the hollow cylinder *s*, being urged on by the spring *x*, moves past the jaws *q* and the kinks *z* and holds the jaws tightly against the lead *r*. In this manner, the lead is fixed in its new position.

70 The pencil illustrated in Figs. 8 to 12 is of similar construction and like parts are indicated by the same reference letters or numerals. In this case, however, a push rod 10 of steel or other suitable metal is engaged by the jaws *q*, instead of a lead, and a lead 11 is inserted in front of the push rod. An extension *e'* is formed at the end of the tube *e* which is somewhat shorter than the inner tube *b*. A store of leads may be kept in the annular space *h'* between the tube *b* and the extension *e'*.

75 A disc 12 is screwed into the end of the inner tube *b* and a tubular extension 13 at the centre of the disc extends into the magazine *h'* and slides on the extension *e'* when the tube *b* is depressed. The tubular extension forms a passage 14. Another opening or passage of a diameter somewhat larger than that of the leads, is formed in the disc 12 at 15. The inner tube *b* may be provided 80 with guiding lugs 16 which will work in slots 17 of the top of the outer tube *a*. A cap *c'* is screwed on the inner tube *b*.

85 The operation of this pencil is the same as that described with reference to Figs. 1 to 7, the steel push rod *n* being fed forward for a given distance on every operation of the tube *b*, and feeding forward the lead 11 for a like distance.

90 When the lead has become exhausted, it is not automatically replaced as in the form shown in Figs. 1 to 7, but the steel push rod 10 is removed from the tube *e*, *e'*, a new lead is placed in the tube and the push rod is reinserted. When a lead has become exhausted 95 the push rod will assume the position shown in dotted lines in Fig. 9 in which its rear end is held by the jaws *q* of the gripper *n*. To release the push rod, the cap *c'* is unscrewed, the end of the inner tube *b* is pressed on a fixed support, a table or the like, and the outer tube *a* is depressed as shown by the arrow 17' in Fig. 9. This opens the jaws *q*, the push rod 10 is released and drops into the position indicated in full lines in Fig. 9, so that it comes out when the pencil is raised from the support. At the same time, a lead drops out from the bore 15 in the disc 12 so that everything required for recharging the pencil is at hand and it is only necessary to insert first the lead and then the push rod 10 in the central bore 14 of the plate 12, and the pencil is ready for use upon replacing the cap *c'*.

I claim:

1. In a propelling pencil, in combination, telescoping inner and outer tubes, a slotted lead-guiding tube secured in said outer tube, a gripper operatively connected with said inner tube and comprising jaws formed on the ends of resilient arms and adapted to pass through the slots in said guiding tube and engage a lead therein, and means operatively connected with said inner tube for controlling said jaws.

2. In a propelling pencil, in combination, telescoping inner and outer tubes, a slotted lead-guiding tube secured in said outer tube, a gripper longitudinally movable in said inner tube and comprising jaws carried on resilient arms and adapted to engage a lead in said guiding tube, and a hollow cylinder operatively connected with said inner tube and provided with a seat adapted to engage and close said jaws.

3. In a propelling pencil, in combination, telescoping inner and outer tubes, a slotted lead guiding tube secured to said outer tube, a gripper longitudinally movable in said inner tube and comprising jaws carried on resilient arms and adapted to engage the leads in said guiding tube, kinks formed on said resilient arms, and a hollow cylinder operatively connected with said inner tube, adapted to engage said kinks and provided with a seat adapted to engage and close said jaws on the lead.

4. In a propelling pencil, in combination, telescoping inner and outer tubes, a slotted lead guiding tube secured to said outer tube, a gripper adapted to be moved longitudinally in said inner tube, and comprising jaws carried on resilient arms and adapted to engage a lead in said slotted guiding tube, means operatively connected with said inner tube for controlling said jaws, and adapted to move said gripper by friction, and a check for limiting the stroke of said gripper.

5. In a propelling pencil, in combination, telescoping inner and outer tubes, a slotted lead guiding tube secured to said outer tube, a gripper adapted to be moved longitudinally in said inner tube, and comprising jaws carried on the free ends of resilient arms and adapted to engage through the slots in said guiding tube, a lead therein, means on said resilient arms adapted to assist in pressing the jaws against a lead, and means operatively connected with said inner tube for controlling said jaws.

6. In a propelling pencil, in combination, telescoping inner and outer tubes, a slotted lead guiding tube secured to said outer tube, a gripper adapted to be moved longitudinally in said inner tube, and comprising jaws carried on resilient arms and adapted to engage a lead in said guiding tube, the gripping surfaces of said jaws being rough-

ened, and means for controlling said jaws operatively connected with said inner tube.

7. In a propelling pencil, in combination, telescoping inner and outer tubes, a slotted lead guiding tube secured to said outer tube, jaws carried on resilient arms and adapted to engage the leads in said guiding tube, means operatively connected with said inner tube for controlling said jaws, a perforated disc at the end of said inner tube, and having a tubular projection thereon adapted to slide over the end of said guiding tube.

8. In a propelling pencil, in combination, telescoping inner and outer tubes, a slotted lead guiding tube secured to said outer tube, jaws carried on resilient arms and adapted to engage a lead in said guiding tube, means operatively connected with said inner tube for controlling said jaws, a disc perforated at two points at the end of said inner tube, and a tubular projection surrounding one of the perforations in said disc and adapted to slide on the end of said guiding tube.

9. In a pencil mechanism, the combination of a longitudinally-movable carrier member formed with an opening therethrough, a longitudinally-movable lead-gripping member formed at one of its ends into a plurality of fingers supported within the opening in said carrier member, said fingers being resiliently held open and adapted to be closed by pressure of said carrier member against the same, means to limit the downward movement of said carrier member and means to limit the downward movement of said gripping member prior to the operation of said last-mentioned means on said carrier member.

10. In a step-by-step pencil, the combination of a longitudinally movable member formed with an opening therethrough, a longitudinally-movable lead-gripping unit extending into said opening and supported upon said member, said unit comprising a tubular portion and a plurality of outwardly-resilient arms extending longitudinally therefrom and formed with lead-gripping portions at their free ends, the periphery of said opening and the cooperating surfaces of said arms being in cam relationship, means providing upper and lower stops for said arms and means for reciprocating said longitudinally-movable member.

11. In a step-by-step pencil comprising a casing, the combination of means providing a magazine, a carrier member formed with a central opening and positioned beneath said magazine, means for reciprocating said carrier member, a longitudinally-movable lead-gripping unit arranged to be supported by said carrier member, upper and lower stops for said gripping unit, said carrier member and said gripping unit being formed with cooperating surfaces whereby said gripping unit will be caused to grip the lead when said unit is moved against said upper stop by

said carrier member, and resilient arms to cause said gripping unit to release the lead upon the withdrawal of said carrier member therefrom when the gripping unit reaches said lower stop.

ly accessible element whereby said operating member may be moved downwardly, said operating member being adapted during its downward movement to maintain the jaws in clamped position until the gripping unit reaches its limit of downward movement and thereupon to release the jaws as said encircling member is carried downwardly and being adapted during its upward movement to move the jaws ahead of said encircling member until the gripping unit reaches its limit of upward movement and thereupon to clamp said jaws, the exterior of said jaws and the interior of said jaw encircling portion being formed with cooperating upwardly and outwardly inclined surfaces.

5 12. In a magazine pencil, comprising an outer shell and a tubular member reciprocable within said shell, means including the upper portion of said tubular member to provide a lead magazine to permit the passage of
10 a plurality of leads successively downwardly therefrom, a carrier member secured to said tubular member, a lead-gripping member, comprising a plurality of outwardly sprung-pressed fingers, said carrier member being formed with a central opening to receive said fingers, the inner surface of said opening and the outer surface of said fingers being in cam relationship and said carrier member being
15 adapted to press the fingers inwardly against a lead in the pencil, said gripping member being longitudinally movable by said carrier member, and upper and lower stops for said gripping member.

15. In a step-by-step pencil, the combination with a casing, of a lead-gripping unit longitudinally movable within the casing and comprising a plurality of outwardly spring-pressed jaws, means to limit the upward and downward movement of said gripping unit, a longitudinally movable operating member including a portion adapted to encircle said jaws and to clamp the same against a lead in the pencil, said encircling portion being disposed in supporting relation to said jaws, means normally to maintain said operating member in an upward and jaw-clamping position, an exteriorly accessible element whereby said operating member may be moved downwardly, said operating member being adapted during its downward movement to maintain the jaws in clamped position until the gripping unit reaches its limit of downward movement and thereupon to release the jaws as said encircling member is carried downwardly and being adapted during its upward movement to move the jaws ahead of said encircling member until the gripping unit reaches its limit of upward movement and thereupon to clamp said jaws, said operating member being formed with recesses adapted to receive said jaws when said encircling portion moves below the same, and means to force said jaws out of said recesses to permit the clamping thereof by said encircling portion when the gripping unit reaches its limit of upward movement.

gripping member.

13. In a step-by-step pencil, the combination with a casing, of a lead-gripping unit longitudinally movable within the casing and comprising a plurality of outwardly spring-pressed jaws, means to limit the upward and downward movement of said gripping unit, a longitudinally movable operating member including a portion adapted to encircle said jaws and to clamp the same against a lead in the pencil, said encircling portion being disposed in supporting relation to said jaws, means normally to maintain said operating member in an upward and jaw-clamping position, and an exteriorly accessible element whereby said operating member may be moved downwardly, said operating member being adapted during its downward movement to maintain the jaws in clamped position until the gripping unit reaches its limit of downward movement and thereupon to release the jaws as said encircling member is carried downwardly and being adapted during its upward movement to move the jaws ahead of said encircling member until the gripping unit reaches its limit of upward movement and thereupon to clamp said jaws.

16. In a step-by-step pencil, the combination with a casing, of a lead-gripping unit longitudinally movable within the casing and comprising a plurality of outwardly sprung-pressed jaws, means to limit the upward and downward movement of said gripping unit, a longitudinally movable operating member including a portion adapted to encircle said jaws and to clamp the same against a lead in the pencil, said encircling portion being disposed in supporting relation to said jaws, means normally to maintain said operating member in an upward and jaw-clamping position, an exteriorly accessible element whereby said operating member may be moved 120 125 130

downwardly, said operating member being adapted during its downward movement to maintain the jaws in clamped position until the gripping unit reaches its limit of downward movement and thereupon to release the jaws as said encircling member is carried downwardly and being adapted during its upward movement to move the jaws ahead of said encircling member until the gripping unit reaches its limit of upward movement and thereupon to clamp said jaws, said operating member being formed with recesses adapted to receive said jaws when said encircling portion moves below the same, and means to force said jaws out of said recesses to permit the clamping thereof by said encircling portion when the gripping unit reaches its limit of upward movement, the exterior of said jaws and the interior of said jaw encircling portion being formed with cooperating upwardly and outwardly inclined surfaces.

17. In a step-by-step pencil, the combination with a casing, of a lead-gripping unit longitudinally movable within the casing and comprising a plurality of outwardly spring-pressed jaws, means to limit the upward and downward movement of said gripping unit, a longitudinally movable operating member including a portion adapted to encircle said jaws, said encircling portion being disposed in supporting relationship to said jaws and said jaws and said encircling portion having cooperating surfaces formed to permit the jaws to be clamped against a lead in the pencil by the continued upward movement of said operating member when the upward movement of the jaws is limited and when in clamped position to be drawn downwardly by the downward movement of the operating member until the downward movement of the jaws is limited, and means independent of the gripping unit for reciprocating said operating member.

18. In a step-by-step pencil, the combination with a casing, of a lead-gripping unit longitudinally movable within the casing and comprising a plurality of outwardly spring-pressed jaws, means to limit the upward and downward movement of said gripping unit, a longitudinally movable operating member including a portion adapted to encircle said jaws, said encircling portion being disposed in supporting relationship to said jaws and said jaws and said encircling portion having cooperating surfaces formed to permit the jaws to be clamped against a lead in the pencil by the continued upward movement of said operating member when the upward movement of the jaws is limited and when in clamped position to be drawn downwardly by the downward movement of the operating member until the downward movement of the jaws is limited, resilient means for normally maintaining the operating member in an upward position and an

exteriorly accessible element independent of the gripping unit whereby said operating member may be moved downwardly.

19. In a step-by-step pencil, the combination of a casing, a slotted lead guide tube secured in said casing, a lead-gripping unit 70 slidable on said guide tube and comprising outwardly spring pressed jaws adapted to extend through the slots in said guide tube to grip a lead therein, means to limit the upward and downward movement of said gripping unit, a longitudinally movable operating member including a portion adapted to encircle said jaws and to clamp the same against a lead in the pencil, said encircling portion being disposed in supporting relation to said jaws, a spring encircling said guide tube and tending to hold said operating member in an upward and jaw-clamping position, and an exteriorly accessible element 75 whereby said operating member may be moved downwardly, said operating member being adapted during its downward movement to maintain the jaws in clamped position until the gripping unit reaches its limit of downward movement, and thereupon to release the jaws as said encircling member is carried downwardly and being adapted during its upward movement to move the jaws ahead of said encircling member until the gripping unit reaches its limit of upward movement and thereupon to clamp said jaws.

In testimony whereof I have signed my name to this specification.
